UNITED STATES PATENT OFFICE.

ADOLPH WILDMANN, OF NEW YORK, N. Y.

KNOCKDOWN PAPER BOX.

SPECIFICATION forming part of Letters Patent No. 783,089, dated February 21, 1905.

Application filed March 22, 1904. Serial No. 199,338.

To all whom it may concern:

Be it known that I, ADOLPH WILDMANN, a citizen of Austria-Hungary, residing at New York, in the county of New York and State 5 of New York, have invented certain new and useful Improvements in Knockdown Paper Boxes, of which the following is a specification, such as will enable those skilled in the art to which it appertains to make and use the same.

10 The object of this invention is to provide an improved knockdown pasteboard or cardboard box of the class used by tailors, clothing dealers, and others for packing clothes and other articles and for shipping the same; 15 and with this and other objects in view the invention consists in a box of the class specified constructed as hereinafter described and claimed.

In the practice of my invention I provide a 20 knockdown box composed of two members—a bottom portion or member and a top or cover portion or member—and these parts or members are made exactly in the same manner, the only difference being in the depth thereof, the 25 top portion or cover being, if desired, of less depth than the bottom portion of the box.

The invention is fully disclosed in the following specification, of which the accompanying drawings form a part, in which the separate parts of my improvement are designated by suitable reference characters in each of the views, and in which—

Figure 1 is a plan view of a blank from which the bottom or body portion of my improved box is made when it is desired to make a square box; Fig. 2, a perspective view showing a blank folded so as to form the box member; Fig. 3, a plan view showing the process of folding the blank so as to form the 40 box member shown in Fig. 2; Fig. 4, an edge view of the box member shown in Figs. 2 and 3 completely knocked down; Fig. 5, a side view of the box member as shown in Fig. 4; Fig. 6, a perspective view of the complete 45 box, the cover or top portion being of less depth than the body or bottom portion; Fig. 7, a sectional detail of the construction on the line 7 7 of Fig. 2; Fig. 8, a view similar to Fig. 1, showing a blank used in making an 50 oblong and rectangular box member; Fig. 9,

a perspective view of a box member made from said blank; Fig. 10, a plan view showing the method of folding the box member shown in Fig. 9 when knocking it down; Fig. 11, an edge view of the box member 55 shown in Fig. 9 completely knocked down; Fig. 12, a side or plan view thereof; and Fig. 13, a perspective view of a box complete, the cover or top member being of less depth than the bottom or body member of the box. 60

In the practice of my invention as shown in Figs. 1 to 7, inclusive, I cut from any suitable pasteboard, cardboard, or similar material the blank shown in Fig. 1, the general form of which is rectangular and square, and 65 this blank comprises a body portion *a*, two folding end portions *b*, and two folding side portions *c*. The side portions *c* are provided at each end with triangular flaps *c*², separated from said side portions by score or folding 70 lines *c*³, and the said side portions *c* are also provided with diagonally-arranged score or folding lines *c*⁴ at their diagonally opposite ends. The folding end portions *b* are also separated from the body portion *a* by score 75 or folding lines *b*², and the body portion *a* is provided with a diagonal score or folding line *a*² parallel with the score or folding lines *c*⁴, whereby said body portion is divided into two similar and equal parts *a*³. Secured to one of 80 the parts *a*³ parallel with the score or folding line *a*² and at a determined distance therefrom is a catch-piece *d*, composed of cardboard, pasteboard, or other suitable material, and this catch-piece *d* is preferably connected 85 with the body portion *a* by means of eyelets *d*², which are arranged at the opposite ends thereof and one of which is farther from the inner edge of said catch-piece than the other, and pivoted to the other part *a*³ of the body 90 portion *a* is a lock-piece *e*, which is connected with said body portion *a* by means of an eyelet *e*², and the lock-piece *e* is adapted to be swung down beneath the catch-piece *d*, as shown in Fig. 2. 95

In forming the box member as shown in Fig. 2 from the blank shown in Fig. 8 the side portions *c* are raised or folded into an upright position and the end flaps *c*² are bent inwardly and the end portions *b* of the blank 100

are then folded into an upright position and the flaps c^2 are secured thereto, preferably by means of eyelets b^3 , although this construction may be made in any desired manner, and when the box member is thus formed the lock-piece e is turned so that the free end thereof passes beneath the catch-piece d , as shown in Fig. 2, and the box member is thus held rigid, the lock-piece e preventing the folding of the body portion a of the blank, which forms the bottom of the box member, along the score or folding line a^2 .

The complete box is shown in Fig. 6, and the bottom or body portion is designated in this figure and in Figs. 2 and 3 by the reference character a^4 , while the top portion or cover of the box is designated by the reference character a^5 , and the top or cover a^5 is formed from a blank exactly the same in shape and construction as that shown in Fig. 1.

In knocking down the box member shown in Figs. 2 and 3 the lock-piece e is turned so that it will not engage the catch-piece d , as shown in Fig. 3, and the bottom of the box member is folded backwardly along the score or folding line a^2 and the side portions c are folded along the score or folding lines c^4 and the said box member is folded into the form shown in Fig. 5, an end or edge view thereof being given in Fig. 4.

As shown in Fig. 6 the top or cover a^5 is of less depth than the bottom or body portion a^4 ; but it will be apparent that said top or cover a^5 may be of the same depth as the bottom or body portion a^4 , in which case the bottom or body portion a^4 would be entirely enclosed by the top or cover.

The construction shown in Figs. 8 to 13, inclusive, is exactly the same as that shown in Figs. 1 to 6, inclusive, with the exception that the box produced is oblong and rectangular in form instead of square. In this form of construction I provide a blank (shown in Fig. 8) the general form of which is oblong and rectangular, and this blank comprises a body portion g , folding end portions h , and folding side portions i , and the folding side portions i are provided with triangular end flaps i^2 , separated therefrom by folding or score lines i^3 , and the side portions i are also provided at diagonally opposite ends with other score or folding lines i^4 and at the other ends with other score or folding lines i^5 . The score or folding lines i^3 are at an angle to the score or folding lines i^2 of about forty-five degrees, while the score or folding lines i^4 are at a very much less angle to the score or folding lines i^3 , this angle being approximately six degrees. The body portion g is also divided diagonally by a score or folding line g^2 , whereby said body portion is divided into two similar and equal parts g^3 , and secured to one of said parts and parallel with the score or folding line g^2 in the form of construction shown is a catch-piece j , composed of cardboard or

other similar material, this connection being made by means of eyelets j^2 , one of which is farther from the inner edge of said catch-piece than the other, and pivoted to the other part g^3 of the body portion g is a lock-piece k , this connection being made by means of an eyelet k^2 .

In forming a box member from the blank shown in Fig. 8 the procedure is the same as that hereinbefore described with reference to Figs. 1 and 2. The side portions i are first raised or folded into an upright position. The flaps i^2 are then folded inwardly, and the end portions h are then raised and secured to the flaps i^2 , this connection being preferably made by means of eyelets o . The lock-piece k is then turned so that the free end thereof passes beneath the catch-piece j , and the box member is held in a rigid position or so that the bottom thereof, which is formed by the body portion g of the blank, will not fold along the score or folding line g^2 .

In Fig. 13 I have shown a complete box made according to this method, said box being composed of a bottom or body portion m and of a top or cover n , and it will be understood that both of these parts or members are made exactly in the same manner, the only difference being that the top or cover n in the form of construction shown is of less depth than the bottom or body portion m ; but said parts or members may be made of the same depth, if desired.

In folding up or knocking down the separate box members the lock-piece k is turned so that it will not engage the catch-piece j , and the bottom portion of the box member, consisting of the body portion g of the blank, is folded backwardly along the score-line g^2 , and at the same time the side portions i of the blank are folded along the score-lines i^4 and i^5 , as shown in Fig. 10, and the completely knocked down box member is shown in Figs. 11 and 12.

From the foregoing description it will be observed that the only difference between the separate forms of construction shown in Figs. 1 to 7, inclusive, and 8 to 13, inclusive, consists in the length of the blank employed in making an oblong box and in the additional score or folding lines i^4 with which the diagonally opposite ends of the side portions i are provided, and it will also be observed that the score or folding lines c^4 in Fig. 1 are at an angle of forty-five degrees to the adjacent score or folding lines c^3 , this arrangement being the same as that of the score or folding lines i^4 and i^5 in Fig. 8.

My improved knockdown or packing box is particularly adapted for use by tailors, clothiers, and other dealers for the purpose of packing or shipping clothing or other articles, and by reason of the construction herein shown and described the separate box members, or the top and bottom of the box, may

be separated and compactly folded together, and this facilitates and cheapens the packing of the boxes and the shipping thereof in quantities, and the said box members may be unfolded and formed into a box whenever desired.

Having fully described my invention, what I claim as new, and desire to secure by Letters Patent, is—

- 1. A knockdown box of the class described, said box being composed of two parts each of which is formed from a blank, said blank being rectangular in form and consisting of a rectangular body portion, folding end portions, and folding side portions, the side portions being provided with folding end flaps and being also scored or marked at their diagonally opposite ends so as to form folding-lines and at an angle of forty-five degrees to the ends of said side portions or to the folding flaps thereof, the body portion of the blank being also provided with a diagonal score or folding line parallel with the last-named score or folding lines, and one of the members formed thereby being provided with a loop-shaped catch and the other with a pivoted lock adapted to engage the catch, substantially as shown and described.
- 2. A knockdown box of the class described, said box being composed of two parts each of which is formed from a blank, said blank being rectangular in form and consisting of a rectangular body portion, folding end portions, and folding side portions, the side portions being provided with folding end flaps and being also scored at their diagonally opposite ends to form folding-lines at an angle of forty-five degrees to the ends of said side portions or to the folding flaps thereof, and said side portions being also provided at the ends opposite the first-named score or folding lines with other score or folding lines at a less angle to the end flaps than that of the first-named score or folding lines, the rectangular body portion being also provided with a score or folding line parallel with the first-named score or folding lines of the side portions, substantially as shown and described.

3. A knockdown box of the class described, said box being composed of two parts each of which is formed from a blank, said blank being rectangular in form and consisting of a rectangular body portion, folding end portions, and folding side portions, the side portions being provided with folding end flaps and being also scored at their diagonally opposite ends to form folding-lines at an angle of forty-five degrees to the ends of said side portions or to the folding flaps thereof, and said side portions being also provided at the ends opposite the first-named score or folding lines with other score or folding lines at a less angle to the end flaps than that of the first-named score or folding lines, the rectangular body portion being also provided with a score or folding line parallel with the first-named score or folding lines of the side portions, and the separate parts of the body portion thus formed being provided with locking devices to hold the box part or member in operative position, substantially as shown and described.

4. A blank for forming box members, said blank being composed of a rectangular body portion and folding side and end members, the side members being provided with folding end flaps, and being also scored at their diagonally opposite ends so as to form folding-lines at an angle of approximately forty-five degrees to the end flaps, the body portion being also scored diagonally, and the side portions being also provided at the ends opposite the first-named score or folding lines with other score or folding lines and forming small degrees to the end flaps, and the separate parts of the body portion being also provided with locking devices, substantially as shown and described.

In testimony that I claim the foregoing as my invention I have signed my name, in presence of the subscribing witnesses, this 19th day of March, 1904.

ADOLPH WILDMANN.
